UNITED STATES PATENT OFFICE

CURTIS B. ILGENFRITZ, OF YORK, PENNSYLVANIA, ASSIGNOR TO UNITED STATES
GLASS COMPANY, OF PITTSBURGH, PENNSYLVANIA, A CORPORATION OF PENN-SYLVANIA

DESIGN FOR A SUGAR BOWL OR SIMILAR ARTICLE

Application filed January 12, 1933. Serial No. 46,808. Term of patent 7 years.

To all whom it may concern:

Be it known that I, CURTIS B. ILGENFRITZ, a citizen of the United States, residing at York, in the county of York and State of Pennsylvania, have invented a new, original, and ornamental Design for a Sugar Bowl or Similar Article, of which the following is a specification, reference being had to the accompanying drawing, forming part thereof. The figure is a front elevation of a sugar bowl showing my new design.

I claim:

The ornamental design for a sugar bowl or similar article, substantially as shown.

CURTIS B. ILGENFRITZ.
